(57) **CLAIM**

The ornamental design for a tray for a water treatment apparatus, as shown and described.

DESCRIPTION

FIG. 1 is a top and front surface perspective view of a tray for a water treatment apparatus according to my new design;

FIG. 2 is a front and bottom surface perspective view of the tray of FIG. 1;

FIG. 3 is a front surface elevational view of the tray of FIG. 1;
FIG. 4 is a section view in elevation taken along the line 4—4 in FIG. 3;

FIG. 5 is a top plan view of the tray of FIG. 1; and,

FIG. 6 is a bottom plan view of the tray of FIG. 1.
